WRAPPED ARTICLE

Edward F. Cornock, Springfield, Mass., assignor
to Package Machinery Company, Springfield,
Mass., a corporation of Massachusetts

Application April 19, 1937, Serial No. 137,676

1 Claim. (Cl. 206—46)

This invention relates to the wrapping of articles having an irregular contour, and will be described in its application to the wrapping of a tooth powder container having a friction top of the cap type. Such articles obviously present difficulties due to the irregular shape of one end. It has heretofore been proposed to wrap articles having one end of reduced size, such as bottles, by enclosing them in a cardboard or corrugated board sheath over which the wrapping was wound circumferentially. This method of wrapping supports the circumferential wrapping satisfactorily, but unless it is permissible to merely tuck the ends of the wrapper inside the sheath it does not completely solve the problem. Particularly where a substantially airtight and dust-proof wrapping is desired this manner of wrapping is unsatisfactory as it requires making and sealing the folds across the open end of the sheath without internal support.

The present invention provides a manner of wrapping an article with an irregular end by means of which a dustproof package may be provided. The invention also serves to permit the wrapping of such articles by automatic machinery. A further object of the invention is to improve the appearance and tightness of the wrapping by eliminating all folds from the irregular end of the article.

Referring to the drawing,

Fig. 1 is a side elevation of a friction or screw top can which will serve as an example of an object with an irregular end which can be wrapped in accordance with the present invention;

Fig. 2 is a top plan thereof;

Fig. 3 is a fragmentary side elevation of the article with a protective cardboard sheath applied thereto;

Figs. 4, 5, and 6 are side elevations showing successive stages in the wrapping of the article, the wrapper being shown in Fig. 4 as partially broken away to avoid interference with other views;

Fig. 7 is a bottom end view of the partially wrapped article showing the formation of the first end tucks;

Fig. 8 is a fragmentary plan view of the article in the same condition shown in Fig. 7;

Fig. 9 is a bottom view of the completely wrapped article; and

Fig. 10 is a perspective view of the wrapped article.

The article chosen for illustration of the improved manner of wrapping is a can designed for tooth powder. It comprises a body 11, and

a top portion 12 secured to the body by a bead 13 and having a perforated neck covered by a friction or screw cap 14. Due to the presence of the bead 13 it is possible to apply a cardboard sheath 15 to the upper part of the can only, 5 the sheath resting at its bottom against the bead and extending at its top substantially to the level of the top of the cap 14. The sheath is made of a section of a cardboard tube, or of a piece of cardboard with its ends secured together, and is of a size to fit snugly over the top portion 12.

The can with the cardboard sheath thereon is then brought into contact with the center of a piece of wrapping material 16 as in Fig. 4, 15 and the wrapper is bent down against opposite sides of the can as in Fig. 5. The wrapper is stretched across the open end of the cardboard sheath and completely covers it, so that no folds occur at this point where there would be nothing 20 against which to press the folds. At the same time that the wrapper is thus folded down, or immediately thereafter, tucks 17 are formed in its sides, and the outwardly extending sides of the wrapper are then turned down in overlapping folds 18 and 19 and secured together by any suitable sealing medium. If the wrapper be of a character having a fusible coating the sealing may be done by heat; otherwise a suitable solvent or adhesive may be used. End tucks 20 (Fig. 7) are then made in the end of the wrapper, and finally the extending end flaps 21 and 22 are folded down in overlapping relation and secured in place as in the case of the side folds.

The finished package is shown at Fig. 10. Since there are no folds at all at the top of the package, where the wrapper bridges across the open top of the sheath, and since the end folds are made against the bottom of the article, a 40 very neat appearance is had. This is particularly true where, as is commonly the case, a transparent cellulose wrapping material is used. It will also be observed that since the wrapping operation starts at the open end of the sheath and proceeds towards the bottom of the article the tightness of the wrapper across the top of the article will be preserved. The top of the article can readily be seen through the transparent wrapper, and the cardboard sheath can 45 be colored or ornamented so that the wrapped article as a whole presents a pleasing appearance. If preferred, the cardboard sheath may extend the whole length of the article instead of terminating at the bead 13.

I claim:

A package comprising a can having a reduced end coupled to the body of the can by an outstanding flange, an open ended sheath mounted on the reduced end of the can and abutting the flange and having its walls adjacent its open end extending at least to the end of the reduced

portion of the can, and a wrapper bridging the open end of the sheath in unfolded condition, the wrapper being folded and sealed along the sides of the can and at the end thereof remote from said reduced end.
